DESIGN FOR A COMBINED COLLAPSIBLE BABY WALKER AND CARRIAGE

Maurice Sacheroff, Cleveland Heights, Ohio

Application May 13, 1938, Serial No. 77,168

Term of patent 3½ years

To all whom it may concern:

Be it known that I, Maurice Sacheroff, a citizen of the United States, residing at Cleveland Heights, in the county of Cuyahoga and State of Ohio, have invented a new, original, and ornamental Design for a Combined Collapsible Baby Walker and Carriage, of which the following is a specification, reference being had to the accompanying drawing, forming part thereof.

The figure is a perspective view of a combined collapsible baby walker and carriage, showing my new design, the view being the same from either side.

I claim:

The ornamental design for a combined collapsible baby walker and carriage, as shown and described.

MAURICE SACHEROFF.
